UNITED STATES PATENT OFFICE.

ISAAC LEVY, OF CHICAGO, ILLINOIS.

COMBINED TABLE AND BED.

SPECIFICATION forming part of Letters Patent No. 315,518, dated April 14, 1835.

Application filed January 16, 1884. (No model.)

To all whom it may concern:

Be it known that I, ISAAC LEVY, a citizen of the United States of America, residing at Chicago, in the county of Cook and State of Illinois, have invented certain new and useful Improvements in Combined Table and Bed, of which the following is a specification, reference being had therein to the accompanying drawings.

10 My invention relates to an improved combination of a table and bed. The object it has in view is to obtain an article of furniture which will serve the double purpose of a table and a bed, and which will therefore occupy 15 but a small space, and be convenient and useful at all times; and to that end the invention consists of the novel combination of certain parts, as will be described and claimed.

Reference will be made to the accompanying drawings, in which Figure 1 is a perspective of the device when used as a table, showing one extension-leaf in position for use and the other in position when not in use; Fig. 2, a side elevation of the same; Fig. 3, a perspective of the device when used as a bed, showing the extensions of the table employed as rests and tables; Fig. 4, a section through the bed, and Fig. 5 a section when folded as a table.

30 Like letters refer to like parts in each view. The main frame of the device is supported on legs B, which may be made removable, if desired, and is provided with bottoms C D, separated sufficiently from each other to form

35 a space, a, in which an extension-frame, E, rests and moves, said frame being provided with a lug, b, which contacts with one end rail of frame A and limits the outward movement of the extension-frame, and this frame is provided with legs F, which also may be made removable, and upon which it is supported, then occupying the position shown in Figs. 2, 3, and 4. Extension E is also provided with a hinged end piece, k, which serves to close

45 the space between the lower edge of the removable piece g, to be hereinafter referred to, and the upper edge of the end of said extension, as shown in Fig. 1. Frame A is provided on each side and at a point above bottom C with plates c c', between which a space, d, is left, the lower plate, c', being provided with notches d', into which projecting pins e

of leaves G are inserted when it is desired to fasten said leaves to the sides of the frame.

It will be understood that the notches d' are 55 of such a size that they will admit the shanks of pins e, but will not allow of the withdrawal of said pins, because of their heads, unless the leaf is slightly raised to bring the shank to the slot or space d. One end of frame A is 60 closed by a stationary end piece, f, while the opposite end, when the device is used as a table, is closed by a removable end piece, g, said end piece g being inserted into suitable grooves formed in the sides of frame A and 65 upon the inner faces thereof, these grooves not being shown in drawings. Hinged to frame A is a frame, H, which, when in the position as shown in Fig. 1, forms the top of the table, said frames A H being held in place by a hook, 70 h, which is adapted to engage with a suitable eye or projecting pin, i, as shown in Fig. 2. To the sides of frame H are secured arms I, provided with sliding catch j, and upon the side edge of the top of said frame are provided 75 projecting pins k', which enter into notches l, formed in the edges of leaves G, when it is desired to utilize said leaves as extensions for the table, as shown in Figs. 1 and 2. In bottom D of frame A are formed grooves, in which 80 move arms J, which may be drawn out from either side of the frame, and are designed to support the leaves G when the device is used as a bed, as shown in Fig. 3, said leaves then serving as rests, this arrangement being found 85 especially desirable in case of sickness.

To change the device from table to bed, the extension E is drawn out, the frame H turned back so as to rest on said extension, and the removable end piece g changed from its original position to the opposite end of the frame A to form a head-board. The interior of frames A H being hollow, there is sufficient space left therein for a mattress, K, a pillow, L, and suitable bed-clothing, if desired. 90

The arms I, described as being hinged to frame H and utilized to support leaves G when they are employed as extensions to the table, may be utilized when the device is used as a bed to support one or both of such leaves, 95 thus forming a suitable table by the bedside, as shown in Fig. 3.

What I claim is—

1. The combination, with hinged frames A

H and leaves G, provided with pins *e*, of plates *c c'*, secured to one frame, plate *c'* provided with notches *d*, as set forth.

2. The combination, with hinged sections 5 A H, of adjustable frame E, provided with legs F, and hinged end piece, *k*, as and for the purpose set forth.

3. The combination, with hinged sections 10 A H, of adjustable frame E, provided with lug *b*, legs F, and hinged end piece, as and for the purpose set forth.

4. The combination, with frame A, provided with bottoms CD, and frame H, hinged to frame A, of adjustable frame E, provided with legs F, and hinged end piece *k*, frame A provided 15 with a recess for piece *k*, as set forth.

In testimony whereof I affix my signature in presence of two witnesses.

ISAAC LEVY.
